US00D829710S

(12) **United States Design Patent** (10) Patent No.: **US D829,710 S**
(45) Date of Patent: ** Oct. 2, 2018

(54) **NOTEBOOK COMPUTER**

- (71) Applicant: **SAMSUNG ELECTRONICS CO., LTD.**, Suwon-si, Gyeonggi-do (KR)
- (72) Inventors: **Hoyoung Seoc**, Seoul (KR); **Dongseok Lee**, Seoul (KR); **Iksang Kim**, Seoul (KR)
- (73) Assignee: **SAMSUNG ELECTRONICS CO., LTD.**, Gyeonggi-Do (KR)
- (**) Term: **15 Years**
- (21) Appl. No.: **29/618,275**
- (22) Filed: **Sep. 20, 2017**

(30) **Foreign Application Priority Data**

(57) **CLAIM**

The ornamental design for a notebook computer, as shown and described.

DESCRIPTION

FIG. 1 is a top front perspective view of a notebook computer showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear bottom perspective view thereof; and,

FIG. 9 is another top view thereof showing an unfolded state of the notebook computer.

The broken lines illustrating portions of the notebook computer form no part of the claimed design.

1 Claim, 5 Drawing Sheets
